HUNTING KNIFE

John B. F. Champlin and Theodore H. Banton,
Little Valley, N. Y., assignors to Cattaraugus
Cutlery Company, Little Valley, N. Y., a corpora-
tion of New York

Application April 6, 1943, Serial No. 482,044

4 Claims. (Cl. 279—95)

This invention relates to an improved hunting knife and more particularly to a novel handle therefor.

As in most devices of this character, the knife comprises, besides other parts, a blade and a tang, but heretofore, difficulty has been experienced in solidly maintaining the washers, which latter form the body or grip of the handle, permanently on the tang.

It is therefore an object of the present invention to permanently lock the several parts of the handle in solid assembled relation so that, in the use of the knife, friction of the hand on the grip may not loosen the washers nor may the handle come apart when emergency of use may demand that it be reliably firm and unyielding.

A further object of the invention is to provide near the outer end of the tang, a stop plate so attached to the tang as to rigidly sustain any end thrust and wherein locking plates will be provided at opposite sides of the stop plate for rigidly securing the stop plate in position.

Another object of the invention is to provide a handle wherein the assembly comprising the stop plate and the locking plates at opposite sides thereof will provide a more or less heavy knob at the outer end of the handle adapted, when the handle is grasped in the hand, to form a stop at the outer edge of the palm, and wherein said knob, by reason of its weight, will also afford balance to the blade.

The invention seeks, as a still further object, to provide a construction wherein the permanency and rigidity of the knob assembly will not be affected by climatic conditions, perspiration of the hand or possible swelling of the washers.

Other and incidental objects of the invention will appear as the description thereof proceeds and in the drawing:

Figure 1 is a side elevation of a hunting knife embodying the present invention.

Figure 2 is a top plan view of the knife.

Figure 3 is a vertical section on the line 3—3 of Figure 2.

Figure 4 is a transverse section showing the inner locking plate.

Figure 5 is a transverse section showing the stop plate.

Figure 6 is a horizontal section on the line 6—6 of Figure 5.

Figure 7 is an end view of the knob assembly.

Figure 8 is a fragmentary section showing a slight variation.

Figure 9 is a fragmentary section showing another slight variation.

In carrying the invention into effect, we employ a blade 10 which is provided with a tang 11 and, as seen in Figures 4 and 7 of the drawing, said tang is rectangular in cross section. 15 Near its outer end, the tang is notched from opposite edges thereof to form a shouldered neck 12 which is, as seen in Figure 5, as compared with the tang, much more nearly square in cross section.

Slipped over the tang 11 to abut the blade 10 is a guard 13 which is preferably of metal, and also slipped over the tang are a number of washers 14 which are preferably of leather, although other suitable material may be employed. 20 As seen in Figures 1 and 2 of the drawing, the washers 14 are graduated in peripheral size to provide a grip 15, the exact contour of which may, of course, be varied.

Abutting the rearmost of the washers 14 is a locking plate 16 lying flat against which latter is a stop plate 17, and abutting flat against the stop plate is another terminal locking plate 18. The preferable shape, which is ovate, of the plates 16, 17 and 18 is best seen in Figures 4, 5 and 7 of the drawing and these three plates cooperate to form a weighted knob 19 at the rear end of the handle of the knife affording balance to the blade. Preferably, the plates are of metal and, if so desired, the plate 18 may be thicker than the others. Also, preferably, the outer face of the plate 18 as well as the end face of the tang 11 is knurled to afford a knurled end face for the knob 19.

Attention is now directed to the fact that, as best seen in Figure 5, the stop plate 17 is provided with a transverse slot 20 adapted to receive the outer end of the tang 11 therethrough. This plate is also provided with an intersecting longitudinal slot 21 adapted to fit the neck 12 of the tang while diagonally opposite corners of the intersecting slots are cut away to provide curved clearance surfaces 22. Thus, the stop plate may be initially slipped over the outer end of the tang 11 in a horizontal position, as shown in dotted lines in Figure 5, when, upon reaching the neck 12, said plate may be given a quarter turn to engage and fit said neck. Further, as will be seen, in the vertical position of the stop plate on the neck, all end thrust, either against the outer face of the knob 19 in one direction, or against said plate from the opposite direction, will be rigidly sustained by the coaction of the stop plate with the shoulders of the notches which form the neck 12 and thus communicated directly to the tang 11. Accordingly, it remains

only to rigidly lock the stop plate in operative position.

It has been discovered that any one of several different means may be employed to lock the plates 16, 17 and 18 in mating relation to form the composite knob 19. In the preferred construction, the three plates are spot welded together at the seams, say at the points indicated at 23. Thus, the three plates will be permanently joined into a solid unit so that the plate 17 may not retrograde either by friction of the hand on the knob 19, when engaged with the grip 15, or under the impact of blows by the knob, or by any pressure exerted by the swelling of the washers 14. A composite handle is thus produced which will be found permanently solid and dependable and which will not be subject to any annoying or disconcerting looseness.

In Figure 8, we have shown a slight variation wherein the three plates of the end knob of the handle are indicated at 24, 25 and 26 respectively. As will be seen, cap screws 27 are employed to bind the plates together.

In Figure 9, the three plates of the end knob of the handle are again shown at 28, 29 and 30 respectively. In this variation, rivets 31 are employed to bind the plates together. Other expedients for the purpose may be used provided the three plates are solidly and permanently united into a rigid composite unit.

Having thus described our invention, we claim:

1. A knife including a blade having a tang, a grip carried by the tang provided with a shoulder, and a composite knob at the outer end of the grip cooperating therewith to form a handle for the blade and including a stop plate slipped over the tang and rotated to a position in engagement with said shoulder for sustaining end thrust on the handle, and means locked against

rotation on the tang as well as locked to the stop plate for securing the stop plate against retrograde movement.

2. A knife including a blade having a tang provided with a shoulder, a grip carried by the tang, a stop plate fitted over the tang and rotated thereon to engage said shoulder for sustaining end thrust on the grip, a locking plate non-rotatable on the tang, and means rigidly securing said plates together for locking the stop plate against retrograde movement cooperating with the locking plate and with the grip to form a composite handle.

3. A knife including a blade having a tang notched near its outer end to provide a neck, a grip carried by the tang, and a composite knob at the outer end of the tang cooperating with the grip to form a handle and including a stop plate slotted at one angle to fit over the outer end of the tang and at another angle to fit said neck whereby the plate may be slipped over the tang and rotated to engage the neck and sustain end thrust on the handle, and a locking plate slotted to non-rotatively fit the outer end of the tang and secured rigidly to the stop plate to lock the stop plate against retrograde movement and form a solid unit therewith.

4. A knife including a blade having a tang notched to provide shoulders, a grip carried by the tang, and a composite knob at the outer end of the tang cooperating with the grip to form a handle and including a stop plate slipped over the tang and rotated to engage said shoulders cooperating therewith for sustaining end thrust on the handle, and a locking plate engaged with the tang and with the stop plate for securing the stop plate against retrograde movement.

JOHN E. F. CHAMPLIN.
